(57) **CLAIM**

The ornamental design for a medicinal container with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of a medicinal container with surface ornamentation;

FIG. 2 is a front view thereof;

FIG. 3 is a left side view thereof;

FIG. 4 is a back view thereof;

FIG. 5 is a right side view thereof;

FIG. 6 is a top view thereof;

FIG. 7 is a bottom view thereof;

FIG. 8 is a perspective view of a second embodiment of a medicinal container with surface ornamentation;

FIG. 9 is a front view thereof;

FIG. 10 is a left side view thereof;

FIG. 11 is a back view thereof;

FIG. 12 is a right side view thereof;

FIG. 13 is a top view thereof;

FIG. 14 is a bottom view thereof;

FIG. 15 is a perspective view of a third embodiment of a medicinal container with surface ornamentation;

FIG. 16 is a front view thereof;

FIG. 17 is a left side view thereof;

FIG. 18 is a back view thereof;

FIG. 19 is a right side view thereof;

FIG. 20 is a top view thereof;

FIG. 21 is a bottom view thereof;

FIG. 22 is a perspective view of a fourth embodiment of a medicinal container with surface ornamentation;

FIG. 23 is a front view thereof;

FIG. 24 is a left side view thereof;

(Continued)

FIG. 25 is a back view thereof;
FIG. 26 is a right side view thereof;
FIG. 27 is a top view thereof;
FIG. 28 is a bottom view thereof;
FIG. 29 is a perspective view of a fifth embodiment of a medicinal container with surface ornamentation;
FIG. 30 is a front view thereof;
FIG. 31 is a left side view thereof;
FIG. 32 is a back view thereof;
FIG. 33 is a right side view thereof;
FIG. 34 is a top view thereof;
FIG. 35 is a bottom view thereof;
FIG. 36 is a perspective view of a sixth embodiment of a medicinal container with surface ornamentation;
FIG. 37 is a front view thereof;
FIG. 38 is a left side view thereof;
FIG. 39 is a back view thereof;
FIG. 40 is a right side view thereof;
FIG. 41 is a top view thereof; and,
FIG. 42 is a bottom view thereof.

The evenly broken lines are shown for the purpose of illustrating parts of the article that form no part of the claim.
